HENRY BLACKFD. PAYNE, OF NOTTINGHAM, ENGLAND, ASSIGNOR OF ONE-HALF TO A. G. JENNINGS & SONS, OF BROOKLYN, NEW YORK.

JACQUARD CARD-PUNCHING MACHINE.

SPECIFICATION forming part of Letters Patent No. 395,075, dated December 25, 1888.

Application filed February 7, 1888. Serial No. 263,262. (No model.) Patented in England September 25, 1885, No. 11,412.

To all whom it may concern:

Be it known that I, HENRY BLACKFORD PAYNE, of Nottingham, England, have invented new and useful Improvements in Jacquard Card-Punching Machines, (for which I have obtained Letters Patent of Great Britain for fourteen years from September 25, 1885, No. 11,412,) of which the following is a specification.

10 The object of my invention is to provide improvements in the "head" of machines for punching holes in cards to be used in Jacquard looms.

15 The invention consists in the details of improvement that are more fully hereinafter set forth.

Reference is to be had to the accompanying drawings, forming part of this specification, in which—

20 Figure 1 is a plan view of my improved card-punching machine. Fig. 2 is a vertical cross-section on the line *c c*, Fig. 1; and Fig. 3 is a front view of the machine.

25 A in the accompanying drawings represents the head of the Jacquard card-punching machine, which may be of ordinary or suitable form. The head A carries on its sides gudgeons *a* or other pivots, which are adapted to rest in suitable bearings, *b*, supported by the machine. The punches B pass into holes *d* in the head A, and are held therein free to slide up and down.

30 Within the head A are a series of holes, *e*, arranged approximately at right angles to the holes *d*. The holes *e* open into the holes *d*, as shown in Fig. 2.

35 D is a series of rods, which pass within the holes *e*, and when moved lengthwise are adapted to pass over the upper ends of the punches B. Each rod D carries at its outer end a thin strip, *f*, of brass or the like. The several strips *f* are contained within an opening, *g*, in the head A. The rods D also carry springs *x*, that are arranged to press the rods D forward or from over the holes *d*.

40 E are a series of longitudinal movable keys or rods carried in the head A, and which preferably extend slightly beyond said head, as shown. These keys or rods E carry on their

inner ends one or more thin strips or wards, *h*, arranged at about right angles to the strips *f*, as shown.

45 The wards *h* may be guided at their ends, if preferred. When a key E is pressed inward, its ward *h* will press inward the strips *f* in its path, and thereby certain of the rods D will be moved over the punches B. As the head A is now lowered to punch the holes in the card F that is upon the die-bed G, the rods D so passed over the punches B will 50 prevent said punches passing up the holes *d*, and will thereby hold the punches B to their work. As it is necessary that one or any desired number of holes may be punched at one descent of the punches, I provide the inner 55 edge of each ward *h* with one or more projecting wards proper, *i*, which will engage a corresponding number of strips *f*.

50 In the drawings I have shown six punches B on each side of the machine. These 70 punches can be used singly or in any desired combination—such, for instance, as the first and third, the second and sixth, and so on. By arranging the projections *i* on each ward *h*, so as to select the desired combination of 75 strips *f* and punches B, only one of the, say, thirty keys E need be pushed in at a time to cover the particular punches B desired. The

number or combination of punches B to be selected by the different wards *h* can be indicated by suitable numbers, words, or other symbols placed on the outer end of the keys E, as shown in Fig. 3. Thus, when it is desired to punch, say, one hole, the key marked, say, "1," will be pushed in, its ward *h* then engaging only the strip *f* for the punch No. 1, only one punch B being thereby brought into use. When more than one hole is to be punched, the key E, denoting the desired number or combination of punches, will be pushed in, 80 when the ward *h*, having the proper number of projections *i*, will select the required number of strips *f* and rods D to bring the correct number or combination of punches B into use. I may also provide keys E' and 85 punches D', set in different positions to punch the gathering peg-holes *b*² and the lacing-holes *b*³. When the head is lowered to punch

90 95

the holes in the card, the punches B that are not engaged by rods D will slide in the holes d, and will therefore not cut the card.

The cards F may be moved along by any 5 suitable means.

To oscillate the head A, I provide said head with an arm or projection, H, on the side most distant from its pivots, as shown in Figs. 1 and 2. This arm H has an opening, j, with- 10 in which works an eccentric or cam, l, carried by a shaft, I, supported in suitable bearings, m. The shaft I may be rotated by a belt, n, passing over fast and loose pulleys o p, or by other suitable means. As the cam l rotates, 15 the head A will be oscillated on its pivots a b; but the cam or eccentric l may be applied to the head A otherwise than by the arm H, if preferred.

It is evident that the strips h could be in- 20 tegral parts of the keys E with the same re- sults. If the inner edges of the strips h were plain and the strips f were provided with notches and wards proper, the same effects would be produced, and such an arrangement

is by me regarded as equivalent to the notch- 25 ing of the wards h.

Having now described my invention, what I claim is—

1. The head A, having the punches B and corresponding rods, D, and the strips f, se- 30 cured to and carried by the rods D, combined with the larger series of keys E, adapted to engage said strips f in prearranged groups to actuate certain of the rods D and lock certain of the punches, substantially as described. 35

2. The head A, having punches B, and rods D, and the strips f, carried by and secured to the rods D, combined with the keys E, and wards h, secured to said keys and wholly sup- 40 ported by said keys, said wards h being adapted to engage prearranged groups of said strips f, substantially as described.

The above specification signed by me this 8th day of December, 1887.

II. BLACKFD. PAYNE.
